UNITED STATES PATENT OFFICE.

JAMES D. BLALOCK, OF CROSS, ALABAMA.

EXCAVATING-MACHINE.

SPECIFICATION forming part of Letters Patent No. 694,240, dated February 25, 1902.

Application filed May 18, 1901. Serial No. 60,878. (No model.)

To all whom it may concern:

Be it known that I, JAMES D. BLALOCK, a citizen of the United States, residing at and whose post-office address is Cross, in the 5 county of Lamar and State of Alabama, have invented new and useful Improvements in Excavating-Machines, of which the following is a specification.

This invention relates to improvements in 10 excavating-machines, and more particularly relates to that class of excavating-machines designed for ditching and in which the bucket-wheel is located within the frame of the machine.

15 The object of the present invention is the provision of a machine of the character stated which shall be extremely simple in construction, yet one which is capable of thoroughly operating upon the ground for the formation 20 of the ditch and having raised the earth will deposit the same either along the line of the ditch or in a suitable conveyance for transporting the earth to a point of deposit.

A further object of the invention is to so 25 construct the machine that the parts thereof will be related in such manner as to be capable of easy separation, and thus provide for expeditious repairs in the event of such being necessary.

30 With these general objects in view and others which will appear as the nature of the improvement is better understood the invention consists in the novel construction, combination, and arrangement of parts, as will 35 be hereinafter fully described, illustrated in the accompanying drawings, and definitely claimed.

In the drawings, Figure 1 is a side elevation 40 of a machine constructed in accordance with the present invention. Fig. 2 is a vertical transverse sectional view thereof. Fig. 3 is a sectional plan view of the machine.

Referring to the drawings, the numeral 1 designates the frame of the herein-described 45 machine, which frame is substantially rectangular in form, and arranged transversely of said frame at a point intermediate its ends and journaled in suitable bearings 2 is a bearing-shaft 3. Mounted upon the shaft 3 within 50 the frame 1 and adapted to rotate therewith and on which the whole machine is balanced is a bucket-wheel 4, said wheel being open at

one of its sides and provided at its other side with a head 5 and circumferential tread 5^a, and arranged upon the inner side of said head 55 is an annular flange 6, to which flange is connected a series of inwardly-projecting teeth 7. The wheel 4 is also provided at its inner side with a series of concave buckets 8, said buckets being arranged in comparatively close relation, but being shallow in depth in order to receive but a small percentage of the earth as the same is excavated. An inwardly-converging annular rim 9 is also arranged at the inner side of the head 5 and projects beyond 65 the inner end of the buckets, the annular flange, and the teeth 7, and said rim is designed to protect said teeth from the earth as the same falls from the buckets 8 upon the conveyer, to be presently described. It will 70 thus be seen that liability of the machine becoming clogged with the excavated earth during its operation is thereby overcome.

The numeral 10 designates a longitudinally-extending shaft, which shaft is arranged with 75 in the wheel 4, and the ends of said shaft are journaled within inwardly-projecting bearing-arms 11, secured to the frame 1 at the open side of the wheel 4. Mounted upon the rear end of the shaft 10 is a lantern gear-wheel 12, 80 which wheel is meshed by the teeth 7, and motion is thereby imparted to the shaft 10 when the wheel 4 rotates. Arranged at the side of the frame 1 in advance of the wheel 12 is a conveyer 13, said conveyer being arranged 85 transversely of the frame 1 and extending beyond the same, and said conveyer comprises a pair of guide-bars 14, the inner ends of which are provided with bearings 15, which receive the forward end of the shaft 10. A 90 pulley 16 is mounted upon the forward end of the shaft 10 between the inner ends of the guide-bars 14, and a similar pulley 17 is arranged at the outer end of said guide-bars mounted upon a shaft 18, journaled in suitable bearings 19. Mounted upon the pulleys 16 and 17 is an endless conveyer-belt 20, which belt is provided at suitable intervals with a series of transverse strips 21 to prevent rolling of the earth deposited upon said belt. 95

To insure the proper deposit of the excavated earth upon the conveyer-belt 20, an inclined guide-plate 22 is arranged at the inner end of the conveyer 13, said guide-plate being adapt- 100

ed to receive the earth as the same falls from the buckets 7; but in order that the earth deposited upon said guide will be precluded falling back into the bucket-wheel 4 as the same is guided onto the conveyer-belt 20 a guard 23 is arranged on the inner end of the guide-bars transversely of the conveyer 13 in advance of the guide-plate 22. It is thus obvious that should any of the earth deposited upon the guide-plate 22 pass toward the inner end of the conveyer 13 such earth will be immediately received by the guard 23 and guided thereby upon the belt 20. The conveyer 13 is supported by a pair of standards 23^a, which standards project upwardly for the side of the frame 1 immediately beneath the conveyer 13, and extending between said standards is a supporting-rod 24, upon which the conveyer 13 rests. Each of the standards 23^a is provided with a series of vertically-alined openings 25, which openings receive the rod 24, and it will thus be seen that by properly positioning the rod 24 in the openings 25 the degree of inclination of the conveyer 13 may be regulated.

To effect the excavation of the earth, a plow 26 is adjustably mounted beneath the conveyer 13, and said plow is adapted to guide the earth as the same is raised thereby into the bucket-wheel 4. Located in advance of the plow 26 is a colter 27 for the purpose of cutting into the earth and severing any weeds or roots in advance of the plow, and journaled upon the forward end of the frame 1, in advance of the colter 27, is a guide-wheel 28, by means of which the machine is steadied in its movements. The frame 1 is also provided with a pair of rearwardly-extending handles 29, by which the operator may control the movements of the machine.

With the parts assembled in the relation described and illustrated the operation is as follows: A team is attached to the forward end of the machine, preferably by chains in lieu of the usual tongue, and as the machine is drawn forwardly it will be seen that the colter 27 cuts the earth, and the plow 26 raises the earth in the usual manner and guides the same into the bucket-wheel 4, where it is received by the concave buckets 8 and carried upwardly thereby. When said buckets arrive at a point above the guide-plate 22, the earth is deposited on the latter and directed thereby onto the conveyer-belt 20. During the movement of the machine motion is imparted through the teeth 8 and the gear-wheel 12 to the shaft 10, and by the latter the conveyer-belt 20 is caused to move over the pulleys 16 and 17. It will thus be seen that as the earth is deposited upon the belt 20 the latter carries the earth to the outer end on the conveyer 13, from which point it is either deposited upon the ground along the line of the ditch being formed or into a suitable conveyance or receptacle, to be taken to any other point of deposit. If it is desired to elevate or lower the conveyer 13 to regulate

the degree of inclination thereof, the same is effected by simply adjusting the rod 24 in the proper openings 25 of the standards 23, and if at any time it is necessary to separate the machine for repairs the conveyer 13, the shaft 10, and the adjacent parts may be readily removed by simply withdrawing the shaft 10 from the arms 11, which arms are so connected to the frame 1 as to permit this result being accomplished.

While the form of the invention herein shown and described is what is believed to be a preferable embodiment of the invention, it will be understood that the latter is susceptible of various changes in the form, proportion, and minor details of construction, and the right is therefore reserved to modify or vary the invention as falls within the spirit and scope thereof.

Having thus fully described my invention, what I claim, and desire to secure by Letters Patent, is—

1. An excavating-machine comprising a frame, an axle mounted on the frame, a bucket-wheel mounted on the axle within the frame and upon which the machine is balanced, constructed with a head at its inner side, and with buckets, an annular ring having laterally-extending teeth and secured to the head, the inwardly-projecting arms secured to the frame at the outer ends and having shaft-bearings at their inner ends, a longitudinal shaft carrying a gear-wheel at its rear end meshed by the laterally-extending teeth, and a pulley at its forward end, the standards secured to the frame, the guide-bars supported at their inner ends on the longitudinal shaft and at their outer ends on the standards, the pulley mounted in the outer ends of the guide-bars, the endless-belt conveyer mounted on the pulleys, and the inclined guide-plate secured to one of the guide-bars within the bucket-wheel.

2. An excavating-machine comprising a frame, an axle mounted on the frame, a bucket-wheel mounted on the axle within the frame and upon which the machine is balanced, constructed with a head at its inner side, and with buckets, an annular ring having laterally-extending teeth and secured to the head, the inwardly-converging annular rim arranged on the inner side of the head and projecting beyond the inner end of the buckets, annular flange and the teeth, the inwardly-projecting arms secured to the frame at the outer ends and having shaft-bearings at their inner ends, a longitudinal shaft carrying a gear-wheel at its rear end meshed by the laterally-extending teeth, and a pulley at its forward end, the standards secured to the frame, the guide-bars supported at their inner ends on the longitudinal shaft and at their outer ends on the standards, the pulley mounted in the outer ends of the guide-bars, the endless-belt conveyer mounted on the pulleys, and the inclined guide-plate secured to one of the guide-bars within the bucket-wheel.

3. An excavating-machine comprising a frame, an axle mounted on the frame, a bucket-wheel mounted on the axle within the frame and upon which the machine is balanced, constructed with a head at its inner side, and with buckets, an annular ring having laterally-extending teeth and secured to the head, 30 the inwardly-converging annular rim arranged on the inner side of the head and projecting beyond the inner end of the buckets, annular flange and the teeth, the inwardly-projecting arms secured to the frame at the 35 outer ends and having shaft-bearings at their inner ends, a longitudinal shaft carrying a gear-wheel at its rear end meshed by the laterally-extending teeth, and a pulley at its forward end, the standards secured to the frame, the guide-bars supported 40 at their inner ends on the longitudinal shaft and at their outer ends on the standards, the pulley mounted in the outer ends of the guide-bars, the endless-belt conveyer mounted on the pulleys, the guard arranged transversely of the conveyer at the inner end of the guide-bars, and the inclined guide-plate secured to 45 one of the guide-bars within the bucket-wheel. 50

4. An excavating-machine comprising a frame, an axle mounted on the frame, a bucket-wheel mounted on the axle within the frame and upon which the machine is balanced, constructed with a head at its inner side, and

with buckets, an annular ring having laterally-extending teeth and secured to the head, 30 the inwardly-converging annular rim arranged on the inner side of the head and projecting beyond the inner end of the buckets, annular flange and the teeth, the inwardly-projecting arms secured to the frame at the 35 outer ends and having shaft-bearings at their inner ends, a longitudinal shaft carrying a gear-wheel at its rear end meshed by the laterally-extending teeth, and a pulley at its forward end, the standards secured to the frame, the guide-bars supported at their inner ends on the longitudinal shaft and at their outer ends on the standards, the pulley mounted in the outer ends of the guide-bars, the endless-belt conveyer mounted on the 40 pulleys, the guard arranged transversely of the conveyer at the inner end of the guide-bars, and the inclined guide-plate secured to one of the guide-bars within the bucket-wheel.

In testimony whereof I affix my signature in presence of two witnesses.
